UNITED STATES PATENT OFFICE.

JOHN W. CHAMPION, OF CORSICANA, TEXAS.

GO-AROUND TONGS FOR DRILLING MACHINES.

Application filed September 29, 1925. Serial No. 59,811.

This invention relates to apparatus for boring wells and has for its object to provide certain improvements in the mechanism employed for gripping and rotating the pipe in the various operations that must be performed, such as screwing and unscrewing the pipe sections.

More specifically, it is an object of the invention to provide tongs for securely gripping the pipe sections and which is adapted for cooperation with the turntable usually found in well-boring rigs.

It is a further object of the invention to provide pipe tongs in which the jaws when in use will always remain in substantially parallel relation.

Another object of the invention resides in the provision of pipe tongs of the above-described character in which the jaws are caused to grip the pipe to a degree which varies with the force applied to the handle of the tongs for rotating the pipe.

Other objects and advantages of the invention will be apparent from the following description when taken in connection with the accompanying drawings, in which:

Fig. 1 is a plan view of the wrench partly broken away,

Fig. 2 is a side elevation of the wrench also partly broken away, and

Fig. 3 is a fragmentary section taken on line 3—3 of Fig. 1.

Referring to the drawings in detail, the numeral 1 designates generally the wrench which includes the semicircular jaws 2 and 3; the former being pivoted at 4 to a lug 5 formed on the arm 6, and the latter being pivoted at 7 to a link 8 which is in turn pivoted to a lug 9 on the arm 6 as indicated by the numeral 10. The lugs 5 and 9 combine to provide a U-shaped terminal on one end of the arm 6.

Each of the jaws 2 and 3 is provided with a substantially semicircular slip 11 which is locked in position by means of the spring-pressed pins 12, and these slips may be provided on their concave surfaces with the keys 13 for biting into the outer surface of the pipe section when the wrench is in use.

In applying the wrench to a pipe section the jaws are first swung into position around the pipe and the clamp or yoke 14 which is pivoted to the end 15 of the jaw 3 is swung

over the projection 16 on jaw 2, after which the screw 17 is turned up until the jaws 2 and 3 are drawn tightly against the wall of the pipe section.

Obviously, it is necessary that the jaws 2 and 3 grip the pipe with considerably more force than is possible by a mere tightening of the screw 17, and it is accordingly an object of the invention to provide a structure whereby the gripping action of the jaws 2 and 3 may vary with the turning force or moment which it is necessary to apply to the arm 6. To this end the jaw 3 is provided with a lug 18 which extends into the space between the lugs 5 and 9 of the arm 6 and which is adapted to be engaged by the lug 9 when force is applied to the arm 6, thereby drawing the jaws 2 and 3 toward each other with a force that varies directly with the lateral force applied to the arm 6.

As hereinbefore stated the present invention is intended for use with the turntable of well-boring rigs, and for this purpose the arm or handle 6 of the wrench is provided with a slidably mounted block 19 for engagement by the pin of the rotary table (not shown).

From the foregoing description taken in connection with the accompanying drawings it will be observed that I have devised a pipe wrench of relatively few parts, which is simple in operation and therefore free from liability of becoming disorganized when in use. It will also be apparent that by means of the simple expedient of pivoting the jaws in the manner shown with the cooperating lugs 9 and 18, I have provided a construction by which an exceedingly powerful grip may be applied to a pipe section, much after the manner of a toggle, and that this gripping action is produced by the force necessarily applied to the wrench arm in screwing or unscrewing the pipe sections. It will also be obvious that the present invention may be embodied in a wrench for use with either right or left-hand threaded pipes.

In accordance with the patent statutes I have described what I now believe to be the best embodiment of the invention; but I do not wish to be understood thereby as limiting myself or the scope of the invention, as many changes and modifications may be

made without departing from the spirit of the invention; all such I aim to include in the scope of the appended claims.

What I claim as new and desire to secure by Letters Patent is:

1. A pipe wrench including a pair of independent substantially semicircular jaws, an arm to which one of said jaws is directly pivoted, a link pivotally connected to the other jaw and to the arm, means for detachably connecting the ends of said jaws remote from said arm, and cooperating means on said arm and one of said jaws to cause the jaws to grip a pipe as the arm is moved laterally.
2. A pipe wrench including a pair of independent substantially semi-circular jaws, an arm to which one of said jaws is directly pivoted, a link pivotally connected to the other jaw and to the arm, means for detachably connecting the ends of said jaws remote from said arm, and cooperating lugs on said link-connected jaw and said arm, whereby the jaws are caused to grip the

pipe as lateral force is applied to the arm. 25

3. A pipe wrench including an arm terminating in a pair of spaced lugs, a pair of substantially semicircular independent jaws one of which is pivoted to one of said lugs, a link pivoted to the other of said jaws and lugs, means detachably connecting the free ends of said jaws, and a lug on one of said jaws for cooperation with one of the lugs on said arm to cause the jaws to grip a pipe as the arm is moved laterally. 35

4. A pipe wrench including an arm terminating in a **U**-shaped portion forming two lugs, a pair of substantially semicircular jaws one of which is pivoted to one of said lugs, a link pivoted to the other of said jaws and lugs, means for detachably connecting the free ends of said jaws, and a lug on one of said jaws and situated within said **U**-shaped portion of the arm, whereby when the arm is moved laterally one of its lugs will engage the lug on said jaw to cause the jaws to grip a pipe. 40 45
